UNITED STATES PATENT OFFICE.

WILLIAM L. LAURENCE, OF BROOKLYN, NEW YORK.

DEVICE FOR ATTACHING CUSHION HEELS.

Application filed June 6, 1922. Serial No. 566,440.

To all whom it may concern:

Be it known that I, WILLIAM L. LAURENCE, a citizen of the United States, residing at Brooklyn, in the county of Kings and 5 State of New York, have invented certain new and useful Improvements in Devices for Attaching Cushion Heels, of which the following is a specification.

This invention relates to devices for assembling a specific cushion heel to a shoe, and the main object is to provide a device which will compress a rubber flange on the heel so that it can be readily inserted into a special recess in the heel.

15 Another object is to provide a device which can be used in connection with various sizes of shoe heels, and is further provided with means for quick release of the pressure.

20 These and other objects will become apparent in the description below, in which similar characters of reference refer to like-named parts in the drawing.

Referring briefly to the drawing, Figure 25 1 illustrates a top plan view of the device when applied to the heel of a shoe.

Figure 2 is a side elevational view of the same.

Figure 3 is a front elevational view of 30 Figure 1.

Figure 4 is a cross-sectional view taken on line 4-4 of Figure 1 and illustrates the cushion heel flange partly compressed.

Figure 5 is a cross-sectional view of a portion 35 of a heel having the cushion heel completely compressed and turned up for insertion into the hollow of the shoe.

Describing the drawing in detail, the numeral 10 indicates a flexible metallic draw 40 band having a permanently curved surface extending in the direction of its width.

An annular disk 11 is rotatably mounted on a shaft 12 and receives the end of the draw band 10 in a slot 13, cut into the periphery 45 14 of said disk. A pin 15 fixed on the surface of the said disk is adapted to be engaged by a lever arm 16, the latter being rotatably mounted on said shaft 12.

A bracket 17 receives the upper end of 50 said shaft 12 at one end and is provided with an extension 18 in which a hole 19 is formed.

A member 20, similar in shape and size to said extension 18 has a circular stem 21 55 engaging in the hole 19 and keeps both

members 18 and 20 in alignment with each other. A spring 22, wound about said stem 21 between the members 18 and 20, normally keeps the latter two members in extended relation to each other. A small pin 23 diametrically disposed in the end of the stem 21 slides in a slot 24 formed in the extension 18, and limits the travel of the slidable members 18 and 20.

As the device embodied in this application is useful exclusively in the mounting of cushion heels, described in an application for Letters Patent filed by me on May 27, 1922, under Serial No. 564,060, I am illustrating the said heel in the various views 70 of the drawing, and a brief description is hereinafter presented.

The upper vamp 25 of a shoe usually has a leather heel 26 secured thereto in a permanent manner. Said heel is provided with 75 an enlarged substantially semi-circular undercut recess 27 having inreaching flanges 28.

Each of the cushion heels 30, which are to be inserted is provided with a neck 28' 80 corresponding, to the opening between the flanges, 28 and of similar contour, and a head 29 similar in contour and proportion to the recess 27 fits therewithin when the cushion heel is secured in place.

In order to secure the cushion heel 30 to the shoe heel 26 the head 29 thereof is bent or up-turned, as illustrated in Figures 4 and 5. This is accomplished by the device, by having the curved band 10 encircle 90 the head 29 and the handle lever 16 when turned in the direction of the arrow, will wind the band upon the disk 11. In this manner the draw band is shortened and the head 29 will be compressed until the edge 95 31 of the latter, projecting above the draw band 10, is reduced enough to be inserted into the opening between the flanges 28.

The lever 16 can then be released and the draw band 10 extended and detached from 100 the cushion heel. The cushion heel will then be disposed adjacent the heel surface and can easily be pushed into place in any convenient manner.

I claim:—

1. A device for assembling a recessed flanged cushion heel to a shoe comprising a draw band having an arcuate cross-section and adapted to partly encircle the cushion heel flange, said band being adapted 110

to turn up the edges of the heel flange, means for contracting the operative length of said band.

2. A device for assembling a recessed flanged cushion heel to a shoe comprising a draw band adapted to encircle the flange of said cushion heel and turn up the edges of the latter when said draw band is shortened, said band having an arcuate cross section, 10 an extensible bar secured to the band, a com-

pression spring interposed between the sections of said bar, a shaft fixed to said bar, a disk rotatable thereon, a pin fixed in said disk, and a handle lever engaging said pin, said handle lever being adapted to rotate 15 said disk and shorten the length of said band.

In witness whereof I affix my signature.

WILLIAM L. LAURENCE.
